CLAIM

The ornamental design for a microphone, as shown and described.

DESCRIPTION

FIG. 1 is a top, front, right side perspective view of a microphone showing my new design;

FIG. 2 is a front view thereof;
FIG. 3 is a back view thereof;
FIG. 4 is a right side view thereof;
FIG. 5 is a left side view thereof;
FIG. 6 is a top view thereof; and,
FIG. 7 is a bottom view thereof.
The broken lines in the drawings depict portions of the
microphone that form no part of the claimed design.

1 Claim, 6 Drawing Sheets
